P. E. CHARLES,

PAD FOR CARRYING RADIO-ACTIVE ORES AND MEANS FOR INCREASING THE ACTIVITY OF THE ORES.
APPLICATION FILED JUNE 15, 1918.

1,317,659.

Patented Sept. 30, 1919.

INVENTOR
Phyllis E. Charles

Edward A. Stause, ATTORNEY,

UNITED STATES PATENT OFFICE.

PHYLLIS E. CHARLES, OF VICTORVILLE, CALIFORNIA.

PAD FOR CARRYING RADIO-ACTIVE ORES AND MEANS FOR INCREASING THE ACTIVITY OF THE ORES.

1,317,659.

Specification of Letters Patent. Patented Sept. 30, 1919.

Application filed June 15, 1918. Serial No. 240,215.

To all whom it may concern:

Be it known that I, PHYLLIS E. CHARLES, a citizen of the United States, residing at Victorville, in the county of San Bernardino and State of California, have invented new and useful Improvements in Pads for Carrying Radio-Active Ores and Means for Increasing the Activity of the Ores, of which the following is a specification.

10 This invention relates more particularly to a heating pad or garment provided with a plurality of pockets designed to carry radio-active ores, such as carnotite, pitch-blende, samarskite, or other radio-active ores 15 in a pulverized form, provided with electro thermal means for greatly increasing the activity of said ores.

It has been ascertained that the activity 20 of emanation in radio-active or uranium ores has been greatly increased by the application of heat thereto.

Radio-active ores have heretofore been utilized by the medical profession for application to the human body to increase the 25 red corpuscles in the blood and also to temporarily increase the white corpuscles. They also increase the secretion of uric acid and sodium biurate in the urine. Such ores when applied to the human body have a 30 general functional tonic effect thereupon, and by their use elimination of waste matter takes place.

An object of my invention is to provide a pad or garment provided with a plurality 35 of pockets on one face thereof designed to carry radio-active ores in a pulverized form so that said ores will be maintained evenly over the surface of the pad or garment.

It is also an object of the invention to apply 40 an electrical circuit in the pad for increasing the radio-activity of the ores carried thereby.

I accomplish these objects by means of the device described herein and illustrated in 45 the accompanying drawing, in which:

Figure 1 is a perspective view of a pad embodying the features of my invention.

Fig. 2 is an enlarged detailed cross section of the pad taken on line 2—2 of Fig. 1.

50 Fig. 3 is an enlarged partial vertical section of the pad taken on line 3—3 of Fig. 1.

Referring more particularly to the drawings, 5 Fig. 5 designates a pad formed of a pliable fabric, and preferably consisting of three plies, 6, 7 and 8. Plies 6 and 7 are stitched

60 together at the edges thereof and carry elec- tric conductors 9, said electric conductors being arranged transversely of the pad, as clearly shown in Fig. 1 of the drawings, from the top to the bottom, the ends of the 65 electric conductors terminating in an electric plug 10, which is designed to be attached to a socket of the usual lighting circuits installed in residences or buildings. The outer ply 8 is stitched to the other plies by 70 means of a plurality of vertically disposed stitches 11 and transversely by a plurality of stitches 12, so as to form pockets 13 for the reception of the pulverized ores 14.

By means of pockets 13 formed between 75 plies 7 and 8, I am enabled to uniformly distribute the ores throughout the surface of the pad.

I have illustrated a heating means for the 80 pad which consists of an electric circuit, but any other means of heating the pad before applying it to the human body, will in all probabilities answer the purpose equally as well as the electric circuit, although the application of the circuit to the pad will maintain a uniform temperature at all times during its use. If desired, the space between plies 6 and 7 may be utilized for carrying a heated fluid.

It will be noted from the above description 85 that I have provided a novel means for increasing the activity of radio-active ores in a manner that will be found extremely efficient in the treatment of various functional diseases of the human body.

90 What I claim is:

1. In a device of the class described, a flexible member having arranged therein, radio-active ore and thermic means secured to said member for increasing the radio activity of said ore.

2. In a device of the class described, a flexible member provided with a plurality of pockets, radio-active ore secured in said 100 pockets, an electric heating circuit carried by said member, and means to connect said circuit to a source of electrical energy.

3. In a device of the class described, a flexible member provided with a plurality of pockets, radio-active ore secured in said 105 pockets and means to heat said members to increase the radio activity of said ores.

In witness that I claim the foregoing I have hereunto subscribed my name this 28th day of May, 1918.

PHYLLIS E. CHARLES.
